SHIPPING DEVICE

Filed April 13, 1928

UNITED STATES PATENT OFFICE.

CLIFFORD L. SNYDER, OF DETROIT, MICHIGAN, ASSIGNOR TO THE EVANS AUTO LOADING CO. INC., OF DETROIT, MICHIGAN, A CORPORATION OF DELAWARE.

SHIPPING DEVICE.

Application filed April 13, 1928. Serial No. 269,759.

This invention relates to shipping devices of the type disclosed in the U. S. patent to R. E. Baus, No. 1,638,612, dated August 9, 1927.

5 The primary object of the present invention is to provide, in a shipping device of the above type, improved means for securing a box against vertical movement on the floor of a freight car or the like during 10 shipment.

As clearly disclosed in the above mentioned patent, it has been customary to extend a cross-piece or solid wooden clamp bar across the top of the box being shipped, 15 and to provide rods for connecting the free end of the clamp bar to the floor, the rods being extended through the ends of the clamp bar and having threaded projecting upper ends on which nuts are applied to 20 secure the clamp bar in place. The use of these solid wooden clamp bars has been found objectionable for several reasons, among which may be noted excessive weight, lack of efficient action in aiding to prevent 25 shifting of the box on the floor, and the presence of objectionable projecting upper ends of the connecting rod, extending above the clamp bar.

An important object of the present invention, therefore, is to provide an improved shipping device of the above kind by means 30 of which the above mentioned objections are overcome in an efficient and economical manner.

35 A more specific object of the invention is to provide an improved box securing means of the above kind including corner irons adapted to engage the upper corners of the box, and a connecting rod adapted to connect 40 the corner irons and extend across the top of the box, whereby the top of the latter is firmly gripped through the medium of a construction eliminating the use of the objectionable clamp bar.

45 Still another object is to provide a form of corner iron of the above kind which is simple in construction and economical to manufacture, and means by which rods may be used for connecting the corner irons to 50 the floor without the objectionable projecting of the upper ends of the latter rods above the top of the box and the corner iron.

A still further object is to provide for

convenient adjustments to enable the box 55 to be firmly secured upon the floor, and to provide simple and efficient means for securing such adjustments after the same are made.

The invention consists in the novel form, 60 combination and arrangement of parts hereinafter more fully described, shown in the accompanying drawing and claimed.

In the drawing:

Figure 1 is a fragmentary perspective 65 view showing a box secured upon the floor of a freight car by a means embodying the present invention;

Figure 2 is an enlarged top plan view 70 of one of the corner irons forming part of the shipping device shown in Figure 1;

Figure 3 is an edge elevational view thereof;

Figure 4 is a side elevational view of the same looking toward the right of Figure 3;

Figure 5 is a fragmentary section taken 75 on line 5—5 of Figure 4;

Figure 6 is a fragmentary section taken on line 6—6 of Figure 4; and

Figure 7 is a plan view of the blank from 80 which the corner iron is formed.

For purposes of illustration, only a single box 5 is shown positioned upon the floor 6 of a freight car or the like, and, means, such as members provided with oppositely 85 disposed projections, may be positioned between the adjacent faces of the box and the floor to prevent shifting of the box as is disclosed in the above mentioned patent.

The present invention has more particu- 90 lar reference to an improved means for securing the box against vertical movement or holding it down on the floor 6 so as to also aid in preventing shifting of the box on the floor. This means generally consists 95 of a pair of corner irons or bearer grips 7 adapted to fit upon and engage the upper side corners of the box 5, a rod 8 extending across the top of the box and connecting the corner irons 7, and further rods 9 connect- 100 ing the corner irons 7 to the floor 6 to secure the box 5 firmly upon the floor.

As shown, each corner iron is formed from a single strip of bar iron of rectangular form and uniform width from end to end 105 as illustrated in Figure 7, the intermediate portion 10 of the strip being bent intermediate its ends upon a transverse line 11 into

angular form as shown clearly in Figure 3 to present portions disposed at right angles to each other and adapted to flatly engage the top and side faces of the box at the upper side corner of the latter as clearly illustrated. In this way the corner iron is adapted to snugly fit and bear upon the corner of the box so that when the two cooperating corner irons are connected and drawn together, they may be connected to the floor by the rods 9 so as to most effectively secure the box against lateral as well as longitudinal and upward displacement. Each end of the strip from which the corner iron is formed is also bent upon a pair of spaced parallel transverse lines 12 and 13 to provide a flange or ear 14 projecting outwardly at right angles to the adjacent arm of the angular intermediate portion 10, and a resilient free end portion 15 disposed at an acute angle to and projecting inwardly from the outer end of the flange 14 to a point coincident with the plane of the associated arm of the intermediate portion 10 as shown in Figure 3. Each flange 14 has a central opening 16 to loosely receive the adjacent end of the connecting rod 8 or 9, while the yieldable end extensions 15 are formed with central longitudinal elongated slots 17 to permit the free passage of the connecting rods 8 or 9 therethrough. It will be particularly noted that the ear 14 of the upper horizontal arm of the corner iron is relatively short so that the end of the connecting rod passed therethrough will be positioned close to the upper arm of the corner iron. A nut 18 is applied to the threaded adjacent end of the connecting rod 8 outwardly of the ear 14, and a flat face of this nut will engage the upper arm of the angular intermediate portion 10 of the corner iron so as to be held against rotation relative to the connecting rod 8. By providing the rod 8 with oppositely threaded ends, it may be turned for adjusting through the nuts 18 whereby the corner irons may be adjusted and drawn tightly against the sides of the box. As the ears 14 are flexed by this adjustment, the free inner or lower ends of the extensions 15 will engage the top of the box so as to thereby be flexed for causing the lower end walls of the slots 17 to engage and bind against the rod 8 for effectively securing the latter against turning after being adjusted. The ear 14 and extension 15 on the vertical arm of the intermediate portion 10 will operate in the same way except that the nut 18^a on the upper end of each rod 9 may be freely turned due to the fact that the nut 18^a is spaced from the adjacent lower end portion of said vertical arm of the intermediate portion 10 as shown in Figure 3. A lock washer 19 is accordingly employed to secure the nut 18^a in adjusted position.

65 The lower ends of the side connecting

rods 9 preferably have the usual hooks adapted to engage the stake pocket 21 or other suitable securing means.

In use, the pair of corner irons are connected by the top connecting rod 8 and adjusted to the upper corners of the box 5 as well as toward each other into engagement with the sides of the box. The upper ends of the connecting rods 9 are then passed through the ears 14 and extensions 15 on the depending arms of the corner irons, and the lower ends of the rods 9 are suitably secured to the floor 6 as at 20. The nuts 18^a are then tightened so that the corner irons are firmly drawn downwardly to effectively secure the box 5 upon the floor 6 against objectionable shifting movement or upward displacement.

In view of the above it will be seen that the present holding or securing means will be extremely light in weight although quite strong and efficient. It will further be apparent that the construction may be readily and economically manufactured as well as easily and expeditiously placed into practical use.

Minor changes may be made without departing from the spirit and scope of the invention as claimed.

What I claim as new is:—

1. Means for securing a box against vertical movement on a floor comprising a pair of angle grips adapted to fit upon the upper side corners of the box, a rod adapted to extend across the top of the box and connecting said angle grips, and other rods for connecting the angle grips to the floor to secure the box thereon. 95
2. Means for securing boxes upon a floor during shipment comprising a pair of box-engaging corner irons, means including a tie rod adjustably connecting said corner irons across the top of the box, and other rods for connecting said corner irons to the floor. 100
3. Means for securing a box against vertical movement on a floor comprising a pair of angle grips adapted to fit upon the upper side corners of the box, a rod adapted to extend across the top of the box and connecting said angle grips, further rods for connecting the angle grips to the floor to secure the box thereon, said angle grips having outwardly projecting ears at the opposite ends thereof to receive the ends of the rods, and nuts adjustably threaded on the ends of said rods and engaging said ears. 115
4. Means for securing a box against vertical movement on a floor comprising a pair of angle grips adapted to fit upon the upper side corners of the box, a rod adapted to extend across the top of the box and connecting said angle grips, further rods for connecting the angle grips to the floor to secure the box thereon, said angle grips hav- 125

ing outwardly projecting ears at the opposite ends thereof to receive the ends of the rods, and nuts adjustably threaded on the ends of said rods and engaging said ears, 5 said angle grips further embodying end extensions engageable with the box and flexible thereby into binding engagement with the rods upon tightening of said nuts.

5. In a means for securing a box upon a floor, a corner iron comprising a single strip of metal having an angular intermediate portion to fit upon a corner of the box, outwardly projecting rod-receiving ears on the ends of said intermediate portion, and 10 flexible extensions projecting inwardly at an acute angle to the ears for contact with the box at their inner ends, said extensions having longitudinal elongated rod-receiving slots and adapted to be flexed to bind upon the rods when the securing means is 15 tightened.

6. In a means for securing a box upon a floor, a corner iron comprising a single strip of metal having an angular intermediate portion to fit upon a corner of the box, outwardly projecting rod-receiving ears on the ends of said intermediate portion, and 20

flexible extensions projecting inwardly at an acute angle to the ears for contact with the box at their inner ends, said extensions 30 having longitudinal elongated rod-receiving slots and adapted to be flexed to bind upon the rods when the securing means is tightened, one of said ears being shorter than the other. 35

7. Means for securing a box against vertical movement on a floor comprising a pair of angle grips adapted to fit upon the upper side corners of the box, a rod adapted to extend across the top of the box and connecting said angle grips, further rods for connecting the angle grips to the floor to secure the box thereon, said angle grips having outwardly projecting ears at the opposite ends thereof to receive the ends of the 40 rod, nuts adjustably threaded on the ends of said rods and engaging said ears, and locking extensions on the ends of the angle 45 grips for securing the rods against turning upon tightening of the nuts. 50

In testimony whereof I affix my signature.

CLIFFORD L. SNYDER.
